(57) **CLAIM**

We claim the ornamental design for a record storage cabinet, as shown and described.

DESCRIPTION

FIG. 1 illustrates a top perspective view of a record storage cabinet showing our new design.

FIG. 2 illustrates front plan view thereof.

FIG. 3 illustrates rear plan view thereof.

FIG. 4 illustrates left side plan view thereof.

FIG. 5 illustrates right side plan view thereof.

FIG. 6 illustrates top plan view thereof.

FIG. 7 illustrates bottom plan view thereof.

FIG. 8 illustrates an exploded bottom front left side perspective view thereof; and,

FIG. 9 illustrates an exploded bottom rear left side perspective thereof.

The broken lines shown in the drawings represent portions of the record storage cabinet that form no part of the claimed design.

1 Claim, 6 Drawing Sheets
